UNITED STATES PATENT OFFICE

LOUIS E. LILGE, OF VALLEYFORD, WASHINGTON

RANGE

Application filed November 16, 1928, Serial No. 319,942. Renewed September 11, 1931.

This invention relates to improvements in ranges, an object being to provide a range which may be positioned within a wall or recess so that only the front of the range **5** will be exposed, and thus conserve space in a small kitchen, as well as reduce labor necessary in cleaning the outside walls of the range.

Another object of the invention is the **10** provision of a range of the above type which is of novel construction, having means to carry off smoke and fumes, so that the latter will not enter the kitchen and travel to other portions of a building, and means **15** to provide convenient compartments for the reception of cooking utensils, the structure providing a pleasing and ornamental appearance when installed for use.

With the above and other objects in view, **20** the invention further includes the following novel features and details of construction, to be hereinafter more fully described, illustrated in the accompanying drawings and pointed out in the appended claim.

25 In the drawings:—

Figure 1 is an elevation with parts broken away showing a range constructed in accordance with the invention.

Figures 2, 3 and 4 are sections taken respectively on the lines 2—2, 3—3, and 4—4 of Figure 1.

Referring to the drawings in detail wherein like characters of reference denote corresponding parts, the range as shown comprises a cabinet or housing which is made up of a front wall 10, side walls 11 and a rear wall 12. Extending horizontally of the housing is a plate 13 having openings for the accommodation of burners 14. This plate **35** forms the bottom of a burner compartment 15 whose top is defined by inwardly inclined walls 16. These walls together with the rear wall 12 terminate in a restricted outlet 17 which is adapted for communication with a flue and which is controlled by a damper 18.

The burners 14 may be either gas or electric burners. In the former event, the burners are controlled by valves 19, and where electric burners are utilized, suitable switches **40** may be substituted for the valves.

The front wall 10 of the housing is provided with openings for the accommodation of drawers 20. These drawers are arranged beneath the burners and provide trays to catch overflow from cooking. The plate 13 **55** is provided with rounded corners to facilitate cleaning and may be removably secured in place. The front portions of the drawers 20 are provided with air inlet openings 21.

Positioned beneath the burners are compartments 22 for the accommodation of cooking utensils and these compartments may be provided with shelves 23 and doors 24. An oven 25 is positioned within the burner compartment and its door 26 is provided with a **60** latch 27.

The front of the burner compartment is open and is adapted to be closed by a closure panel 28. This panel is mounted for vertical sliding movement in guides 29 provided in the side edges of the front wall 10, the upper portion of this front wall providing a panel **70** 30 which extends upward in front of the inclined walls 16 and above the open front of the burner compartment 15. **75**

If desired, this burner compartment may be provided with an electric lamp 31.

The construction shown and described provides a cabinet range which may be positioned within an opening or recess in the wall of a room with the front wall flush with the wall of the room, so that only the front wall of the range will be exposed. The closure panel may be operated to entirely close the front of the range so that the burners will be hidden while the panels may be suitably ornamented. The burner compartment when closed will form a warming oven where cooked food may be kept warm for an appreciable period. A handle 32 may be provided on the closure panel to facilitate operation of the latter and this handle may have removable engagement with a resilient member 33 to hold the panel open. **85** **90** **95**

The invention is susceptible of various changes in its form, proportions and minor details of construction and the right is herein reserved to make such changes as properly fall within the scope of the appended claim. **100**

Having described the invention what is claimed is:—

A range comprising a substantially rectangular shaped casing having the front wall terminating in a plane below the sides and rear walls and having the top and side walls inclined towards the rear wall to provide a restricted outlet to the casing, said casing adapted to be located in a recess of a wall of
10 a room, a frame extending upwardly from the front wall in front of the top wall, a panel located in the frame and extending from the upper edge of the front wall to a plane above said top wall to conceal the inclination of the top wall and the outlet, a heat compartment in the casing, means to heat the compartment, and a door slideable in the frame to close the heat compartment when in one position and adapted to slide upwardly in
15 front of the panel when desiring to open said compartment.
20

In testimony whereof I affix my signature.
LOUIS E. LILGE.
